UNITED STATES PATENT OFFICE.

ALFRED A. WAITE, OF WILMINGTON, DELAWARE.

DESIGN FOR A TOOTH-BRUSH HOLDER.

SPECIFICATION forming part of Design No. 27,690, dated September 28, 1897.

Application filed July 24, 1897. Serial No. 645,864. Term of patent 31 years.

To all whom it may concern:

Be it known that I, ALFRED A. WAITE, a citizen of the United States, residing at Wilmington, in the county of New Castle and State of Delaware, have invented and produced a new and original Design for Tooth-Brush Holders; and I do hereby declare the following to be a full, clear, and exact description of the invention, such as will enable others skilled in the art to which it appertains to make and use the same.

My invention relates to a new design for a holder for tooth-brushes; and it consists, essentially, in a shield-shaped plate having one or more oval pockets on its front, as will be hereinafter fully described and set forth.

In the accompanying drawings, Figure 1 is an elevation of a tooth - brush holder constructed in accordance with my design. Fig. 2 is a plan view of the same.

In the said drawings the reference-numeral

1 designates the base-plate having the curved sides meeting at a central point 2 at the bottom and the top also curved at 3 and meeting at a central point 4.

The numeral 5 designates a number of oval-shaped pockets 6, alternately rising from the center toward the ends or in steps, as shown in Fig. 1.

A holder constructed as above, while possessing great utility as a holder for tooth-brushes, will also present an attractive and ornamental appearance.

What I claim is—

The design for a tooth-brush holder as herein shown and described.

In testimony whereof I affix my signature in presence of two witnesses.

ALFRED A. WAITE.

Witnesses:

CHARLES GREEN,
H. G. PENNINGTON.
